LABEL PRINTER

Harmon P. Elliott, Watertown, Mass., assignor
to the Elliott Addressing Machine Company,
a corporation of Massachusetts

Application July 17, 1937, Serial No. 154,155

14 Claims. (Cl. 101—48)

This invention comprises certain improvements in the general type of apparatus shown and described in my Patent No. 2,015,552, dated Sept. 24, 1935, for a Wrapper printing and addressing machine, and relates more specifically to improvements in means for applying a classification marking to a label, wrapper or the like, adjacent to the stenciled address thereon, to indicate the class of catalogue to be sent with the package, to which the label on which the name and address is being printed is to be affixed, before delivery thereof.

In the patent referred to provision is made for applying such a classification marking automatically by punching the stencils to form differently positioned contact openings through which a circuit is closed to energize one of severally electrically actuated printing devices to apply a catalogue class indication adjacent to the stencilled address.

In such previously patented apparatus there is a separate mechanism for applying each catalogue marking, whereas in my present invention but one apparatus is required which is adjustable to print any one of four different marks on the label being addressed, and that apparatus is merely a simple attachment to the reciprocating pressure platen of the main, address stencilling apparatus.

Also in the present invention the printing of some one catalogue marking can be made continuously on successive labels, and the selection of which one can be made manually by the operator who is running the machine. All this is distinguished from the patented apparatus in which such selection is predetermined and controlled by punching a hole in each stencil frame and becomes thus fixed.

To guide the operator in such selection while using the present invention I make use of the old idea of marking on an extension of the stencil frame, and preferably on the back thereof as has become standardized practice in certain commercial types of stencil addressing apparatus, certain indicia such as records of previous purchases by the customer whose name and address are cut in the stencil. This requires that the stencils shall run through the machine with their backs uppermost, while in my patented apparatus the reverse arrangement is employed as in most machines of the Elliott type, and this similarly requires that the type and inking devices for the label marking shall be under the paper, which reverses the arrangement shown in my said prior patent.

Again, this general rearrangement requires that the web of paper on which the label markings are being printed shall run over the stencil, thus masking the selection controlling indicia unless some way to avoid that difficulty has been devised, and this said difficulty I have overcome by causing the stencils to be fed toward the operator side-wise of the stencilled panel, while the paper web is fed sidewise across his field of vision and then causing the enlarged portion of each stencil frame on which the sales records appear to project beyond the near edge of the paper web so that the operator can see it and easily read such record. Obviously, if the reverse arrangement shown in my previous patent were retained in which the stencils are run endwise of their panels with the paper web lying across the frame extension any such legends which must be written on one of the longer sides of the stencil frames would be covered by the paper web.

Another object of the present invention is the provision of means whereby any one of the catalogue markings may be automatically printed on all the labels, in case the selection is determined by geographic location of the customers, for instance, and all stencils of addresses in any particular location or type of location are segregated in particular magazines so that all of that class are run through the machine at one time. This will be useful in case one type of catalogues lists goods for urban customers while another deals with rural requirements, etc.

Finally, an object of the invention is the provision of simple, manually operated purging means by which the operator may eliminate from the set of stencils going through the printing zone any which should be eliminated therefrom for any reason. Furthermore the feeding actions of two mechanisms on the web are rendered exactly equal.

The invention also has for its further object certain minor structural improvements in the elements cooperating for the general purpose above described, which will be hereinafter pointed out.

The best form of apparatus at present known to me suitable for embodying my invention is illustrated in the accompanying five sheets of drawings, in which

Fig. 1 is a top plan view of the machine.

Fig. 2 is a central vertical cross section on the line 2—2 of Fig. 1 with the power mechanism, which is ordinarily located near the base of the machine, omitted.

Fig. 3 is a vertical longitudinal partial sec-

55

tion on the irregular line 3—3 of Fig. 1, taken at right angles to that of Fig. 2.

Fig. 3a is a continuation to the left hand of Fig. 3, the section being taken centrally of the paper web at the left hand end of the machine.

Fig. 4 is a detail plan view on an enlarged scale, with portions of the table top broken away to show the mechanism illustrated in Fig. 5.

Fig. 5 is a vertical sectional view on the line 5—5 of Fig. 4, with parts broken away.

Fig. 5a is a detail view of the pin pressure-plate of the label marker and a portion of the main stencil printing head on which it is mounted, the same being shown in proper position relative 15 to the mechanism illustrated in Fig. 5.

Fig. 6 is a view showing a portion of the mechanism of Fig. 5 adjusted in a position to produce continuous repetitions of one selected catalogue marking, and

20 Fig. 7 shows one of the labels which has been printed and marked by the machine.

Referring to the drawings, the product of the present machine is a label, wrapper or the like of the type shown in Fig. 7 on which there has 25 been printed a symbol having a predetermined significance, in addition to a name and address. This printing is done on a web of paper fed step by step through the machine and after the printing operation is completed each printed label is 30 cut off the end of the web, which is advanced step by step through the machine. The present purpose of the machine illustrated is to print a symbol indicating the class of catalogue or other publication or the like which should properly be 35 sent by the clerk who wraps up or ships the package to which the label is pasted. Thus the letter L in Fig. 7 means "large".

In the present embodiment of the invention, the stencils are fed forward from the rear of the machine in line with and directly towards the operator and come into printing position under the paper web, which latter travels at right angles to the stencil line of feed.

The stencil proper, in printing position, is 45 concealed from view of the machine operator by the overlay of the paper web, but this does not matter as it is wrong side up for reading and an extension stub of the stencil frame projects beyond the web and presents visible notations, indicating to the operator the class of catalogue 50 to be sent to each stencilled address, and by manipulation of the code-letter printing device the operator adjusts the same so that the proper symbol will be printed on the web at the same time the address is printed.

In the specific construction of machine here shown a flat horizontal table 5 is employed to carry the mechanism. The operator of the machine is ordinarily seated at the front of the 60 table in line with the stencil feed and printing mechanism, the former extending centrally across the table from rear to front thereof.

The stencil addressing mechanism includes a magazine or stencil holder 6, the construction and operation of which is well known in the art and therefore need not be described in detail.

Leading toward the printing zone from the stencil holder there is the usual stencil track, 70 consisting of a pair of grooved, spaced rails 7, 71, that extend transversely across the table to a receiving rack or holder 8, in which the stencils normally are deposited by the feed action, after the printing operation.

75 The stencils 9 (see Fig. 1) have the usual

cardboard reenforcing frame 10, which is extended at one side, as indicated at 11, to provide space for sales data and/or other notation for the guidance of the machine operator in selecting the code classification letter or mark to be printed on the label with the address, as above described. 5

The stencils are placed in the magazine or holder 6, face downward, with the stencil panel towards the rear and the annotated extensions toward the front of the table, as shown in Fig. 1. 10

The lowermost stencil in the magazine or holder at any one operation is pushed out from under the stack into and along the track grooves in the usual manner by a pusher 12, which is vibrated in the line of the track by an arm 13 suitably connected to be actuated by the power which drives the whole mechanism, but which is not shown. The arm 13 is vibrated continuously while the power mechanism is in operation and feeds a stencil from the stack into the track at 15 each movement thereof toward the printing zone.

The printing mechanism comprises the printing roller 14 (see Fig. 2) located below the rails of the stencil track and a reciprocating platen 15, that is located above the track. 25

The printing roller 14 is revolvably mounted between upwardly extending arms 16 of a yoke 17, carried by a rearwardly extending arm 18 integral therewith and disposed centrally of the yoke, said arm being pivoted at 19 to the frame of the 30 machine. The printing roller 14 is given motion into and out of contact relation with the stencil above it by a cam 20 (pivoted at 20a) which, through rod 21 extending from the power mechanism, is oscillated in time with the intervals 35 in the feed motions of the stencils, and the web.

The printing roller 14 is supplied with ink through an idler roller 22, forming part of an inking mechanism not necessary to describe in greater detail since it may be anything suitable 40 or well known in the art.

The platen 15 is mounted between downwardly projecting lugs 23 of a rocker frame which is formed of a pair of side arms 24, connected at the front and rear by cross bars 25, 25. The 45 rocker frame is journaled to oscillate in bearings 26 on the machine frame and extends below said bearings, being provided (centrally of its rear cross bar 25) with a downward extension carrying a roller 27. This roller is so placed as to engage the rear face 28 of the cam 20 by which the rocker frame is given the motion required to move the platen into and out of printing relation with each stencil and with the ink carrying roller 14, while such stencil is resting in printing position. 50

After passing through the printing zone, the stencils are given further intermittent forward movements in the guides and normally are deposited in the receiving rack or holder 8 in the usual manner. The construction of the receiving rack or holder here shown is well known in the art and it will therefore not be necessary to describe the same in detail, as any suitable form 60 may be employed.

As the legends on the back of a particular 65 stencil may indicate that for some reason it should be eliminated from the particular stack being used, I have provided a simple and convenient device which can be brought into operation when desired to deposit any particular stencil in a separate receiver and which, on the other hand, when not so used serves to ensure the deposit of the used stencils in the main receiver 70 8. This is indicated in Figs. 1 and 2 and comprises the small supplemental receiver 95 sup- 75

ported on the horizontally swinging arm 96 and normally located in the line of movement of the stencils outside of the main receiver 8, and a switch plate 97 pivoted on a horizontal axis 98 over the mouth of main receiver 8. A compression spring 99 normally holds this plate in an inclined position as shown in Fig. 2 so that each oncoming stencil then strikes its under surface and is positively deflected downward into the main receiver. When, however, the operator wishes to switch a given stencil into the supplemental receiver 95 this plate can be swung by raising its extension handle 100 (Fig. 1) so that its edge nearest the end of the stencil track comes below said end and the next stencil will then slide over the plate and into the supplemental receiver for discard or transfer to some other stack.

Whenever the accumulated stack of used stencils in main receiver 8 is to be removed the supplemental receiver 95 can be temporarily swung to the right (looking at Fig. 2) to afford access to the stack of stencils in the main receiver.

In order to apply a selected catalogue classification marking to the paper adjacent to such stencilled address and simultaneously in the operation of stencilling such address, a type bar 29 (Figs. 1 and 5) containing a number of code letters or other suitable characters 30, is mounted in guides 31, extending along one side of and in parallel relation to the stencil line of feed, as shown in Fig. 1. The guides 31 are so arranged as to enable the type bar to be moved endwise to bring any selected code letter thereon into position under pin platen 32 near one edge of the stencil about to be used in address printing. Normally this type bar is withdrawn from such printing position and is yieldingly held thus in such position by a spring 29^b, secured at one end to the frame of the machine and at the other end to a stud or pin 29^a depending from the under side of said bar (Fig. 5). This stud or pin 29^a is also utilized in a manner to be later on described to move the type bar into a printing position and bring the desired character thereon under pin platen 32, which is mounted on the rocker frame 24, 25, carrying the stencil platen 15, and moves up and down with the latter.

This pin platen has a vertical screw thread adjustment 33 in its mounting on the rocker frame, permitting it to be raised or lowered to vary the pressure exerted by it on the type face beneath it so that a proper impression can be produced in the printing operation. The face on the lower end of the pin platen may be of rubber or other suitable cushioning material to coat yieldingly with the type below it.

Cooperating with the type bar there is an ink roller 34 carried by an arm 35 pivoted at 36 to a bracket 37. The bracket is removably secured to the table by a set screw 38 and the ink roller is yieldingly held to contact with the face of the type by a spring 39.

As here shown, there are four code letters on the type bar but any number may be used and to enable any one of the letters to be slid into position with speed and certainty and without requiring either skill or undue exertion on the part of the machine operator, provision is made for effecting instant adjustment by merely pressing a button. Preferably as many buttons are employed as there are type faces, one for each character on the type bar, and the buttons are marked with the character of the type bar they are designed to control, as indicated at 40 in Figs. 1 and 4.

Separate and independent connections are pro-

vided from each button to the pin 29^a of the type bar and as these connections are substantially identical, a description of only one set will be given.

The buttons, suitably spaced apart, are arranged in a row and for convenience of operation are located near the front of the table, at the left of the stencil track as shown at 40 in Fig. 1. Each button is secured at the upper end of a vertically disposed rod or bar 41 (Fig. 5) which passes through a slot 42 in the table and projects sufficiently above the upper surface thereof to provide clearance for movement of the button when it is pressed downward to move its particular character on the type bar into position for printing operation. Each bar 41 is pivotally connected at its lower end to one arm 43 of a bell crank which turns loosely on a short cross shaft 44. Attached to the other arm 45 of each bell crank there is a spring 46 which acts to yieldingly maintain the button normally above and clear of the table top. The upper end of each bell crank lever arm 45 has a pin and slot connection 47 with the free end of a link bar 48, the other end of which is pivotally connected at 49 to a horizontally disposed lever 50. Each lever is pivoted at 51 (see Fig. 4) and its opposite free end 52, supported and steadied by one of the guides 53 (Fig. 5), projects into engaging relationship with the pin 29^a of the type bar 29.

As any one button is pressed downward, its connection with its bell crank lever gives the latter counterclockwise movement (Figs. 5 and 6) against the action of its spring 46 and this motion, transmitted through its link bar to its horizontally disposed lever 50, causes the free end thereof to engage the pin 29^a of the type bar and advance the bar in the guides from nonprinting position to one of its printing positions. The extent of movement given the free ends of any lever 50 determines which of the several characters on the type bar will be brought into printing position, and by spacing the connections between the bar links 48 and the levers 50 at different distances from the common pivot 51 of said levers, the movement of the free end of each is graduated as required so that each advances the type bar far enough to bring its corresponding character directly under the pin platen 32 for the printing operation.

If for any reason the type bar characters fail to properly respond to a pressed button, an adjusting means should be provided by which the downward movement of any one or more of the buttons may be varied as required to in turn increase or decrease the movement of the levers 50 until proper registration is obtained between the type bar characters and the pin platen.

For this purpose each of the bell crank levers is provided as here shown with an adjustable stop in the form of a setscrew 54 (Figs. 5 and 6) by which the movement imparted to its connected lever 50 may be carried as required, and through the connections described a corresponding variation will be effected in the movement of the type bar 29. The setscrews 54 are carried by a cross bar 55 secured by brackets 56 to the main frame of the machine.

When addresses in any considerable number are to be printed to which the same catalogue is to be sent, provision is made for utilizing power driven mechanism to automatically repeat the printing of the classification marking for each address stencilling operation and so save the machine operator the time and labor of repeatedly pressing the same type bar shift button.

The effect of this adjustment is to cause any

one of the bellcrank levers 43, 45, to be actuated by power rather than by hand through the buttons 40, as above described.

As the shifting of the type bar bearing the classification markers must be in timed relation to the oscillating movement of the printing head carrying the platens, the platen rocker frame 24, 25, is utilized as a convenient source of power, and transmission of motion from the rocker frame 10 to a cross shaft 57 is effected by a connecting rod 58 pivoted to a crank 59 on the end of 57 as shown in Figs. 2, 4 and 5. The connecting rod 58 is suitably constructed to be elastically extensible lengthwise, as shown in Fig. 5, to compensate for movement of the platen rocker frame 24, 25, in excess over the movement required for the power operation of the classification marking mechanism. In the construction shown in Fig. 5 this is accomplished by having the free 20 end of rod 58 slide in a slotted housing 102 which is pivoted to the rocker frame and has a spring 101 confined between one end of the slot and the end of that rod. The cross shaft 57 extends in parallel relation to the shaft 44 carrying the bellcrank levers 43, 45, and is mounted in extensions 25 of the supporting brackets 103 for that shaft.

From the foregoing it will be seen that in the operation of the stencil printing mechanism, the cross shaft 57 will be oscillated in time with the 30 oscillations of the printing head and in order to selectively transmit this motion of the cross shaft 57 to any one of the bell-crank levers 43, 45, by which the classification characters on the type bar are adjusted to printing position, 35 four identical devices are employed, one for each bellcrank lever.

These devices comprise four crank arms 59^a each fast on the shaft 57. Pivoted at the outer end of each crank arm 59^a is a link 60 which is 40 also pivotally connected to the inner end of a key lever 61 and is normally held against upward movement by a spring 62. The key lever extends beyond the front edge of the machine table and terminates in a button 63 conveniently accessible 45 to the hand of the operator and marked with one of the classification characters of the type bar 29.

As shown in Figs. 1 and 4 there are four buttons 63 arranged in a row, in alignment with the buttons 40, each aligned pair of buttons having 50 corresponding markings.

The alignment of the two sets of buttons brings the key levers in line with the vertically disposed arms 45 of the bell crank levers but normally there is no engagement between them. On 55 depressing a key lever button 63 to shift it from its normal position shown in Fig. 5 to the adjusted position shown in Fig. 6, the link 60 is swung up so that the oscillating motion imparted to the key lever by its carrying shaft will be 60 transmitted to the aligned bellcrank lever, as indicated in broken lines in Fig. 6, which in turn transmits it through a link bar 48 and lever 50 to the classification type bar 29. The effect of this adjustment is to cause a classification character on the type bar, corresponding to the character on the depressed key, to be moved into printing position under the pin platen 32, for each operation of the printing head and to continue this action as long as the adjustment is 65 maintained by holding the key depressed. While this could be done by hand for a few printing operations, it would not be satisfactory where the repeat action of the classification marking is required for a large number of addresses the 70 stencils for which may fill an entire file drawer,

and to enable the repeat key to be releasably locked as adjusted a pin and slot connection is provided between the key lever and its crank arm 59^a of a form such that the pin 64 on the crank arm rides freely in the slot 65 of the key lever as the latter is being depressed, but on full depression the pin snaps into an offset terminal notch 66 of the slot as shown in Fig. 6, where it is held under the tension of the spring 62 until released by the operator.

As previously stated, successive labels are formed from a long sheet or web 67 of paper contained on a roll 68, journaled rotatably upon the frame at the right hand end of the machine table, as viewed in Figs. 1 and 3. The sheet from 10 the roll 68 passes between two guide rods 69 and thence around three feeding rolls 70 that are closely assembled and of relatively small diameter, so that the paper makes sharp bends around them. The rolls are geared together as 15 indicated at 105 in Fig. 1 and one of the rolls, as the roll at the left when looking at Fig. 3, has a positive driving connection through bevel gears 71 and continuously rotating shaft 72, driven by a sprocket chain 73 from the power 20 mechanism. The rolls are not in contact one with another and therefore exert a friction feeding action on the web which is not effective unless it is under tension. This tension is normally maintained by the floating slack take-up 25 roll 74. From the rolls 70, the sheet runs downwardly in a loop around this roll 74, which is normally supported by the loop and guided for vertical movement between pairs of rods 75 so that it is free to move vertically without becoming 30 displaced horizontally. The pairs of rods are provided at their lower ends with stop members 76 which support roll 74 if the loop of the web 67 allows it to drop that far. With this arrangement, when the paper loop is short enough 35 to hold the tension roll above the supports, the weight of the tension roll puts enough tension on the sheet to bring the feed rolls 70 into action and draw the sheet from the roll 68. When, however, the loop is long enough so that 40 the tension roll rests on the supports, the paper loop is relieved from the weight of the roll and hence the frictional engagement between the sheet and the rolls 70 is reduced and the sheet 45 advance is reduced or ceases. The paper web 50 passes upwardly from the lefthand side of the loop (see Fig. 3) and thence horizontally over an idler roll 77, through parallel guides 78, and through the stencil printing zone to the rotating printing sectors at the left hand side of the 55 machine shown in Fig. 3a.

These rotating sectors print the same legend on each label section of the web, as hereinafter explained, and also form the main web feeding mechanism, giving it the intermittent, step-by-step movements necessary for cooperation with the reciprocating stencil printing mechanism. It would not be practical to have this intermittent feed mechanism alone move the whole length of web passing through the machine and so be jerking it off the roll 68 intermittently. Consequently the supplemental web-feeding rolls 70 are used and run continuously to pull the web from roll 68. To allow the uniform motion given to the web by them to be changed into the intermittent 70 movement required in the printing and cutting zones the floating slack take-up roll 74 is used as hereinbefore described. While the web portions in the printing zones are at rest, roll 74 drops gradually as rolls 70 continue to feed the 75

5 righthand portion of the web forward from roll 68. When the feed sectors 90 (Fig. 3a) begin to operate they are timed to pull along in about a quarter of a machine cycle a whole label length 10 of paper, while rolls 70 will only feed that much during an entire cycle. Consequently while sectors 90 are in action take-up roll 74 is being lifted up. When the sectors release the web and friction finger 80 brings it to a stop and holds it 15 stationary for about three quarters of a cycle, roll 74 gradually drops down to take up the slack of the right hand portion of the web being fed out by rolls 70, and so on.

15 The advantage of the light friction feeding action of rolls 70, and the cessation of that while that portion of the web is free from other feeding tension, arises from the fact that this takes care of any slight inequality between the feeding rates of the two feeding mechanisms 90 and 70. 20 The rolls 70 should be geared to have a circumferential movement during each cycle very slightly in excess of a label length, while sectors 90 feed such length exactly. Consequently the length of the free loop carrying the floating roll 74 will 25 slowly lengthen until at the end of some period of rest of the web in the printing zone said roll will rest on its stop 76, and as tension on the web portion then coming through rolls 70 is accordingly released they will slip on the web and it 30 will stop moving until the next slack take-up operation lifts roll 74. Consequently just the length of web required by the feeding apparatus at the left hand side of the machine (which is thus the dominating feed mechanism) will always be delivered by rolls 70 to the printing zones, 35 and no more.

40 It will be observed that the course of travel of the paper sheet, as above described, is across the table at right angles to the line of feed of the stencils and, on reaching the stencil printing zone, the sheet passes over and above the stencils and under the printing head carrying the platen 15 and in this position receives the imprint from the stencil and a marking from type 45 bar 29, both on its under side.

45 From the stencil printing zone the sheet, continuing in the line of travel as above described, passes between a pair of parallel guides 79 and under a spring finger 80, which engages the sheet 50 with sufficient tension to hold it against backward movement when the printing mechanism beyond the tension finger 80 is idle and the sheet consequently is not being advanced thereby.

55 The printing mechanism last above referred to 55 may be employed to apply the sender's name and address, instructions to the postmaster and other general matter common to all labels. As shown in Fig. 3a it comprises a printing roller 81 carried by a shaft 82, mounted in suitable bearings 50 below the paper web and a cooperative rotary platen 84 of the sector type, carried by a shaft 85 (which also carries sectors 90), mounted in suitable bearings 86, above the web, the arrangement being such that the imprint is applied to the under side of the web adjacent to each address thereon, as indicated at 4 in Fig. 7.

60 The printing roller shaft and the platen shaft are geared together, as indicated at 87 (Fig. 1) 60 to rotate in opposite directions at the same speed and the printing roller shaft is suitably geared to be driven by the sprocket chain drive 73 which in turn is rotated by bevel gearing from shaft 72, as shown in Fig. 3.

65 Cooperating with the printing roller 81 there

is the usual inking mechanism indicated in part at 88. Pressing down on the plain surface of the roller 81 at each end beyond the type section are the previously described web feeding sectors formed by the raised arcuate sections 90 5 of predetermined circumferential extent that are designed to engage and give forward feed to the paper for a time during each cycle of operation. This movement is equal to the length of one label, and so timed as to properly locate the matter printed by roller 81 with relation to the addresses previously stencilled on the web. 10

15 Beyond the printing mechanism just described, a paper cutter is provided for cutting off each label section from its web. The cutter shown 15 is of well known form and consists of a fixed blade 91, and a movable blade 92. The movable blade is pivoted at 93 (see Figs. 1 and 3a) and is suitably connected at its free end with the power mechanism, as indicated at 94, to be given 20 up and down movement about its pivot in timed relation to each period of rest of the web. As the completed labels are cut from the web, they fall into the receptacle 104 located below the 25 knife.

25 As will be apparent from the foregoing, the advance of the paper web from the tension device 80, within the lateral guides 79 is brought about by the feed action of the sectors 90 by which it is moved step by step through the 30 printing mechanism to the cutter. The radii of the arcuate sections 90 are, of course, equal to the radii of the arcuate platen 84.

35 As the operation of the various devices employed in the machine has been explained in sufficient detail to be clearly understood, it will not be necessary to further describe the same, but it may be added as to the general operation that the feed of the paper web and the line of stencils is step by step, in timed relation. The 40 stencil pusher 12 and paper feed discs 89 acting in unison present a new section of the paper web for an impression as each stencil comes into printing position and the printing is done in the intervals between the feed stops. 45

45 The selection and adjustment of the catalogue classification mark to accompany each stencilled address is made by the machine operator. Guided by the data or class mark on the stencil frame backs, the operator presses correspondingly 50 marked buttons of either the upper set or the lower set, depending upon whether the mark is to be used for a single address or only successively for several, or whether it is to be used for a large number of addresses calling for the same catalogue. If for a single address or successively for a small number, the upper set of buttons is used and the selected button may be pressed to move the classification marker into position, for each 55 stencil printing operation or it may be pressed and held down until several operations have been completed. Where the number of successive stencils calling for the same class mark is large, the operator uses the outer set of buttons and, as the selected button is pressed down, it adjusts the 60 power drive to automatically move the classification marker into desired position as the stencils are successively advanced into the printing zone. The self-locking action of the buttons of the lower set, when depressed, causes the power drive to 65 continue in effective operation until the button is released by the operator.

65 The provision of the rather complicated duplicate mechanisms for reciprocating the type bar into and out of printing position during each 70 75

cycle of operations of the apparatus results from the necessity of re-inking the type after each operation. If the buttons 40 are being used each one should be manually released after each cycle of operations even if the catalogue marking used is repeated, because if left in operating position there will be insufficient ink on the type face left after any one operation for a repetition thereof. Similarly where one of the buttons 63 is used the type bar is automatically reciprocated into printing position and out again under the inking roller 34 during each cycle of operations. The importance of the web feeding system having an automatic, self-adjusting action, and comprising the slightly separated friction rolls 70 running at a circumferential speed very slightly in excess of that needed to feed one label length during one cycle combined with the compensating, slack take-up action of floating roll 74 with its automatic release of tension on the web portion passing through said rolls at the moment when just the right length of web has been pulled off roll 68 by them (as previously described), arises from the practical impossibility of making two positively acting spaced-apart feed mechanisms operating on a continuous web run at exactly the same speed. That is to say, if the rolls 70, or any two of them, were set so close together as to positively pinch the web between them and the web length so fed by them during any one cycle of machine operation slightly exceeded that fed by sectors 90, web slack would gradually accumulate in the stencil printing zone and interfere with proper registry of the address printed there with the repeat matter 4 printed by roll 81. On the other hand, if such web length so fed by rolls 70 were slightly less than the required amount to even the most minute extent, the web portion between rolls 70 and sectors 90 would as a result be subjected to gradually increasing tension until it broke somewhere between 70 and 90.

Various changes in details of mechanism for producing this and other modes of operation hereinbefore described could be made without departing from the essence of the invention so long as the general mode of operation and results hereinbefore set forth are preserved.

Having described my invention, I claim:

1. In a label printing and addressing apparatus comprising a plurality of address-bearing stencils, a reciprocable member adapted for pressing ink through successive stencils, means for feeding such stencils successively through the printing zone of such apparatus, means for feeding a web of paper also through said printing zone and apparatus for cutting it into a series of sections each bearing a stencilled imprint, a supplemental printing device operatively attached to and in part carried by said reciprocable member adapted for also printing one or another of a series of selected marks on each such label section.

2. An apparatus such as defined in claim 1 in which such stencils are fed toward that side of the apparatus at which it is most convenient for the operator to stand while said web feed is adapted to move it at right angles to said line of stencil movement above and across the line of stencils but in such position as to leave exposed to the operator's view an extended portion of the stencil frame nearest to him on which records of significant data have been made.

3. A label printing and marking apparatus comprising a supporting horizontal frame with guides thereon extending toward that side of the frame at which the operator can most conveniently be located, a series of stencil cards arranged

face downward in said guides and having data marked on their exposed upper surfaces nearest such operator's location, means for applying ink to the under surface of each stencil when in a given position in said guides, means for feeding a web of paper above and across said guides over said ink-applying means so that a portion of the frame of any stencil there located protrudes under the adjacent edge of the paper web, and manually controllable, selective means adapted to mark distinctively the under face of such paper at a point outside of but adjacent to the border of said stencil; whereby the operator can select such marking as may conform to any data exposed on such stencil then in the printing zone.

4. An addressing apparatus comprising, in combination, means for advancing a web of paper and means including a moving line of stencils for applying different addresses in succession and suitably spaced apart for individual use to the under side of such paper web advanced by the first mentioned means, the line of movement of the stencils being at an angle to the direction of feed of the paper and so disposed with reference thereto as to cause a considerable portion of the frame of each stencil when in printing position to be visible beyond the adjacent edge of the paper web; whereby the user may be guided in operating the apparatus by any indicia appearing on such protruding frame portion.

5. An apparatus such as defined in claim 4 combined with means for printing on the under side of such web immediately adjacent to each such address and simultaneously with the printing thereof a mark related to such indicia.

6. An apparatus such as defined in claim 4 combined with manually operable selective means for printing on the under side of such web any one of a plurality of marks indicating the class of catalogue to be sent with any package to which the label simultaneously being printed is to be attached.

7. An apparatus for printing a series of names and addresses on a web of paper fed step by step through the printing zone thereof which comprises a reciprocating platen head and a cooperating, oppositely reciprocating ink-bearing member, combined with a second platen member mounted on said head with its free end adjacent to, and having a face lying substantially in the plane of said first mentioned platen, a type-carrying bar adapted to slide in a plane parallel and opposite to the face of such second platen, mechanism for reciprocating said bar so that any type face thereon may be moved into and out of registry with said second platen member during a portion of each printing cycle, and means for applying ink to such type face while out of such position of registry.

8. In a label printing apparatus employing a plurality of card stencils each having an extension frame on which selection-controlling indicia marked thereon will be visible when the stencil bearing it is in printing position, supplemental mechanism for applying a classification symbol successively to any desired number of such labels while the main legends are being printed thereon comprising, in combination, a reciprocating platen member, a cooperating type bar reciprocable at right angles to the line of reciprocation of said platen member and having a plurality of type formed on its surface which faces said member, an inking device cooperating with said type-bearing surface, mechanism for reciprocating said bar and a plurality of push buttons, one for each

5 type appearing on said bar; said last mentioned mechanism being adapted to move said bar through the inking zone into position to place opposite said platen member the particular type corresponding to any particular push button which may have been pressed by the operator after he has noted the indicia visible on the stencil then to be utilized in printing a label.

9. In a label printing apparatus employing a 10 series of address bearing members and an apparatus cooperating in such printing in successive cycles of operation, supplemental means for applying a particular mark to each label comprising in combination, a platen located near the first 15 above mentioned apparatus, a cooperating type bar movable toward and from said platen, an inking device for the type on said bar located near said platen, and mechanism automatically operable by said first mentioned apparatus for moving said type into cooperation with said inking device before each label printing operation.

10. An apparatus such as defined in claim 9 in which said main printing apparatus comprises a reciprocating member, and said last mentioned 20 mechanism comprises a motion-transmitting 25 connection therefrom to said type bar.

11. An apparatus such as defined in claim 9 in which said main printing apparatus comprises a reciprocating member, and said last mentioned 30 mechanism comprises a motion-transmitting connection therefrom to said type bar, together with manually controllable means for disabling it.

12. In a mechanism for printing one or another 35 of a series of supplemental markings on a sheet on which a longer legend is being printed, the combination of a longitudinally reciprocable bar having type formed in its face along the line of its reciprocation, a single reciprocating platen adapted to cooperate with any one of said type, 40 a series of levers having a common pivot at one end and loosely connected to said type bar

at the other, and a series of type selecting members having substantially uniform limits of movement, but connected to said levers at different distances from their common pivot; whereby, on moving one or another of said members through 5 its path, the type bar will be slid a greater or lesser distance so as to bring into cooperation with said platen the type corresponding to the member which has been moved.

13. In a device adapted to be operated either 10 manually or automatically so as to print one or another of a series of classification or other marks, the combination of a series of cranks each 15 manually rotatable separably about a common axis to effect the printing of a given mark, a second series of cranks fixed on a shaft parallel 20 to said axis, each one of said second cranks moving substantially in the plane of one of the first series, power means for continually oscillating 25 said shaft, and a member on each crank thereon adjustable so as to either engage and vibrate the corresponding member of the first series of cranks or vibrate idly, thereby leaving the selection and printing of any particular marks to be determined by manual operation of one of said first series. 25

14. An apparatus such as defined in claim 8, which is supported from a horizontal table in which said push buttons are set along a straight line, combined with power means for reciprocating said type bar in the selective manner described in said claim, comprising a second row 30 of the same number of push buttons set in a line parallel to that in which the first mentioned ones are arranged and opposite thereto, together with mechanism adapted to automatically reciprocate 35 said type bar whenever one of said second set of buttons is depressed so as to bring it into the same printing position as would be the case if the corresponding one of said first set of buttons had been manually depressed. 40
